JOHN PRIMROSE, OF RICHMOND, NEW YORK, ASSIGNOR TO FOSTER WHEELER CORPORATION, OF NEW YORK, N. Y., A CORPORATION OF NEW YORK

METHOD OF HEATING OIL

Application filed July 2, 1923. Serial No. 648,974.

The general object of the present invention is to provide an improved method of and apparatus for heating oil especially devised and adapted for use in the so-called cracking processes of refining petroleum. More specifically, the object of the invention is to effect the combustion of the fuel burned to heat the oil in such manner as to provide a relatively large weight of heating gases per pound of fuel burned with a relatively low maximum heating gas temperature, while at the same time maintaining a satisfactory thermal efficiency.

In ordinary oil cracking processes it is usually desirable to heat the oil to a temperature of something like 700 or 800° F. the exact temperature depending somewhat on the character of the oil treated and on the particular process followed. A desirable form of apparatus for heating the oil to the proper cracking temperature comprises a multiplicity of tubular heater or retort pipe elements which are mounted in a suitable furnace or retort housing and through which the oil treated passes and is progressively heated. In approved modern forms of such retort furnaces, a considerable portion of the heat generated in the furnace may be transmitted to the oil heater elements or retorts proper by direct radiation from the flames in the retort furnace chamber and from the refractory inner walls of the retort housing, but in all cases, a large portion of the heat absorbed must be transmitted to the heater elements or retorts proper, by contact with the heating gases sweeping over them. In practice, the transfer of heat from the gases to the oil heaters or retorts by contact in amount sufficient to cool the heating gases down to an exit temperature which is low enough from the standpoint of the thermal efficiency of the furnace, requires a path of heating gas flow in contact with the oil heater elements or retorts which is of appreciable length, and in which the heating gases progressively decrease in temperature along this path. The portions of the oil retort heating surface in different parts of the retort furnace are therefore exposed to very different temperatures, varying from the initial temperature of combustion down to the exit temperature of the heating gases, which in practice is ordinarily somewhat above the cracking temperature.

In the operation of oil cracking retorts, overheating of any portion of the retorts proper, is very objectionable, since in an oil cracking process, very complex chemical reactions occur, and the nature of these reactions depend largely on the temperature at which cracking occurs, though it may be modified somewhat by the pressure of the oil. In general when petroleum is cracked, there are formed a heavy oil residue, free carbon, permanent gases, and condensable vapors. The condensable vapors are the valuable products of the process, and it is to obtain those products that the process is carried on. The effect of increasing the cracking temperature above that desired and required, is to decrease the amount of valuable condensable products recovered, and to increase the amount of relatively valueless permanent gases, and free carbon produced. The free carbon produced is positively and substantially objectionable in that it forms a coating on the retort walls and tends to clog up the retorts. The coating of carbon on the retort walls reduces the heat transfer capacity of the apparatus, and what is much more important it greatly increases the liability of the retort walls to be overheated to the point of destruction.

In accordance with the present invention I supply substantially more air to the retort furnace for the combustion of fuel therein than is required for the efficient combustion of the fuel burned. The effect of this is to correspondingly increase the weight of the heating gases generated by the combustion of

a given weight of the fuel, and to correspondingly reduce the temperature of combustion, or maximum heating gas temperature. The resultant reduction in furnace chamber and heating gas temperature directly reduces the danger of local overheating portions of the retort heating surface subjected to the higher temperatures, and desirably increases the effectiveness of the portion of the retort heating surfaces absorbing heat by contact from the heating gases, since the heat absorbing capacity of that surface depends on the velocity of heating gas flow past it. The increased weight and lowered temperature of the heating gases also makes the heat absorption by contact more uniform along the length of the gas path of flow in which this contact occurs. In other words, it makes the heat absorption per unit of retort heating surface adjacent the exit point of the heating gases substantially nearer a parity with the heat absorption per unit of retort heating surface at the entrance end of that path.

Increasing the amount and reducing the initial temperature of the heating gases as described, substantially increases the amount of heat carried out of the retort housing proper, by the heating gases, and wasted, if these gases pass directly to the stack, but in accordance with the present invention, I minimize this disadvantage by utilizing the available heat in the heating gases leaving the retort furnace to preheat the air supplied to the retort furnace for the combustion of the fuel, and for the production of the desired quantity of heating gases.

In the accompanying drawings I have diagrammatically illustrated a preferred form of apparatus for carrying out my invention.

Of the drawings:

Fig. 1 is a plan; and

Fig. 2 is an elevation partly in section.

The apparatus shown in the drawings comprises a unit consisting of two retort furnaces A, and a stack B. Each furnace A, as illustrated, comprises two chambers A' and A² separated by a bridge wall A³. The chamber A' is the combustion chamber into which the fuel burned, and the air for its combustion are introduced. As shown the furnace is heated by the combustion of oil supplied through the pipe C, though it will be understood that the furnace may be gas or coal fired. D represents the air inlet to the chamber A'. The oil heaters or retorts proper comprise tubular elements E, E' and E². The elements E are located in the side walls of the chamber A', and the elements E' are located in the roof over the chambers A' and A², and these elements are intended to absorb heat mainly by direct radiation, and are constructed in known manner to adapt them for this service. The elements E² constitute a

bank of tubes through which the heating gases pass to the retort furnace outlet F. The outlet F of each furnace is directly connected by a corresponding flue F' to the stack B. Each flue F' is provided with a normally closed damper G located between branches F² and F³ of the flue F' leading to the inlet and outlet, respectively of an air heater H. The latter, in the particular construction diagrammatically illustrated, comprises tubes H' into which the heating gases pass from the flue F' through the branch F and from which they pass back to the flue F' through the branch F³. Ordinarily I consider it desirable to supplement the stack suction on each air heater outlet by interposing an exhaust fan I between the heater outlet and the branch flue F³ proper. Each air heater H is provided with an inlet H' through which atmospheric air passes into the intertube space of the heater, and an outlet from this space through which air is conducted by a flue or conduit D' to the furnace air inlet D.

In the operation of the apparatus shown in the drawings, the amount of heating gases passing through each furnace A' at any instant, and the initial temperature of combustion or maximum heating gas temperature will obviously depend on the rates at which fuel and air are supplied to the furnace, as well as on the character of the fuel and the temperature to which the air is preheated in the heater H. The relative amounts of fuel and air supplied can obviously be regulated by suitable adjustment of the oil regulating provisions such as the supply valve C', and by regulating the draft, as by regulating the speed of the corresponding exhaust fan.

The following comparison of results obtainable with and without the use of the invention illustrates characteristic advantages of the invention. Assume for example, that an oil heating furnace is to absorb ten million B. t. u.'s per hour that the fuel is oil giving 18,500 B. t. u.'s per pound, that the heating gases leave the furnace proper at a temperature of 850° F., that the specific heat of the gases is .25, that the efficiency of heat transfer from the heating gases, to the retorts is .95, and that the furnace efficiency is .90. If with the assumptions made, the maximum furnace temperature is 2500° F., which when the air for combustion is not preheated would be as low as would ordinarily be considered desirable from the standpoint of overall efficiency, each pound of heating gases would supply 392 B. t. u.'s $(2500 - 850) \times .25 \times .95 = 392$. With each pound of heating gases furnishing 392 B. t. u.'s, 25500 lbs. of heating gases would be required to furnish ten million B. t. u.'s, and each pound of oil burned would give about 27½ pounds of oil vapor and air at a temperature of 2500 degrees F., if the oil and air for combustion

were supplied to the furnace at a temperature of 60°

$$\left(\frac{18500 \times .90}{(2500 - 60) \times .25} = 27.5 \right).$$

5 Under these circumstances the oil required to furnish ten million B. t. u.'s would be 925 lbs.

$$\left(\frac{25500}{27.5} = 925 \right).$$

10 This would give an overall thermal efficiency of 58.5%

$$\left(\frac{10,000,000}{925 \times 18500} = .585 \right).$$

15 If instead of supplying air for combustion at 60° F., the air is preheated in the heaters H to a temperature of 400° F., and the air and oil are supplied at such relative rates as to give a maximum furnace chamber tem-

20 perature of 2000° F., each pound of heating gases will furnish about 273 B. t. u.'s $(2000 - 850) \times .25 \times .95$, and about 36630 pounds of heating gases would be required

$$25 \left(\frac{10,000,000}{273} = 36630 \right).$$

With the oil supplied at 60° F., and the air supplied at 400° F., each pound of oil burned would give about 40.8 pounds 30 of oil vapor and air at a temperature of 2000° F. $(40.8 \times (2000 - 400) \times .25 + 1 \times (400 - 60) = 18500 \times .90$, approximately). There would thus be required about 897 pounds of 35 fuel oil per hour, and the overall thermal efficiency would be about 60.2%.

The use of the invention under the conditions assumed above therefore increases the overall thermal efficiency, while at the same time permitting a reduction in maximum furnace temperature from 2500° F. to 2000° F. This reduction in maximum furnace chamber, as already explained is highly desirable, and amounts to a very substantial improvement in operating efficiency, as it tends to a 45 better yield of the valuable condensable products, and reduces the liability of trouble from retort overheating and carbon deposits.

The particular form of furnace illustrated 50 comprises novel features of combustion and arrangement devised by me but not claimed herein as they are claimed in my copending application, Serial No. 611,932, filed Jan. 11, 1923. While this furnace is well adapted for use in carrying out the present invention, those skilled in the art will understand that 55 the present invention may be used with many different types and styles of furnaces.

Having now described my invention, what 60 I claim is new and desire to secure by Letters Patent, is:

The method of operating an oil still which 65 consists in burning fuel in an enclosed space, supplying air in substantial excess of the amount required for the combustion of the

fuel to substantially lower the temperature in said space and to substantially increase the volume of combustion gases, absorbing heat by direct radiation from said space and transferring it to oil circulating in said space, passing the products of combustion and the excess air mixed therewith into a second enclosed space, cooling said gases during their passage to said second space by transferring heat by convection to circulating oil, and utilizing the remaining heat in said gases for heating oil circulating in said last-mentioned space and preheating substantially all of the excess air supplied to said first enclosed space before its entrance thereto.

Signed at New York in the county of New York and State of New York this 29th day of June A. D. 1923.

JOHN PRIMROSE.
